UNITED STATES PATENT OFFICE.

ALBERT A. HUSEBY, OF CHICAGO, ILLINOIS.

AUTOMATIC STARTING AND STOPPING DEVICE FOR TALKING-MACHINES.

1,289,784.

Specification of Letters Patent. Patented Dec. 31, 1918.

Application filed April 5, 1918. Serial No. 226,797.

To all whom it may concern:

Be it known that I, ALBERT A. HUSEBY, a citizen of the United States, residing at Chicago, in the county of Cook and State 5 of Illinois, have invented certain new and useful Improvements in Automatic Starting and Stopping Devices for Talking-Machines, of which the following is a specification.

10 This invention relates to the art of talking machines, and has reference more particularly to an improved mechanism for automatically starting and stopping the motor of the machine at the beginning and 15 end of the playing of a record. More specifically, the invention belongs to that type of automatic motor controlling mechanisms wherein the control is effected by the swinging movements of the tone arm, and wherein 20 the mechanism can be set, in advance of the playing of a record, so as to arrest the motor at the completion of the record regardless of the length of the latter.

The principal object of the invention is 25 to provide an improved and simplified automatic starting and stopping mechanism that shall be certain and reliable in its action, shall occupy but little space in the mechanism of the machine, shall be capable of 30 being manually set to effect the stopping of the motor at any desired point in the inward swing of the tone arm, and shall be well adapted to that type of machine employing a vertically pivoted horizontally swinging 35 tone arm in association with a stationary underlying horn or amplifier. With this and other objects in view, which will be apparent from the following detailed description of the invention, the latter consists in the 40 novel parts and combination of devices for effecting the purposes of the invention substantially as hereinafter described, and more particularly pointed out as to subject matter and scope in the appended claims.

45 My invention, its mode and principle of operation, and advantages inherent therein, will all be readily understood and appreciated by those skilled in this art from the following description, taken in connection 50 with the accompanying drawings forming a part of this specification, in which—

Figure 1 is a top plan view of the supporting table or platform of a talking ma-

chine, with the usual turn table omitted for greater clearness, and with the forward portion of the tone arm broken off. 55

Fig. 2 is a bottom plan view of Fig. 1.

Fig. 3 is a fragmentary front elevation, including the motor and brake mechanism, as viewed from the bottom of Fig. 1. 60

Fig. 4 is a view of the parts shown in Fig. 3 as seen from the right of the latter.

Referring to the drawings, 5 designates the horizontal table or platform of the machine which, in practice, is mounted at the upper end, and below the lid or cover of the usual talking machine cabinet (not shown). This table or platform, as usual, supports the turn table and tone arm on its upper side and the motor and motor controlling mechanism on its underside. In the drawings 6 designates the tone arm which is pivotally mounted to swing about a vertical axis indicated at 7 and which communicates with an underlying horn or amplifier, not herein shown, since it forms no part of the present invention. 70

Rigidly secured to the tone arm 6, as by screws 8, is a forwardly extending arm 9 having its forward end a bent extension 10 80 formed with an outer curved or cam edge 11 for a purpose hereinafter disclosed.

Pivoted at 12 (Fig. 2) to the underside of the table 5 and lying against the latter is a flat bar or strip 13, the free end of 85 which rests upon a guiding and supporting strip 14 that is secured at its ends to the underside of the table as by bolts 15. Slidably mounted in guide lugs 16 and 17 depending from the bar 13 is a rod 18. Keyed 90 on this rod are two collars 19 and 20, between which lies the upper end of an arm 21, felt washers 22 being preferably interposed between the arm 21 and the collars 22 to eliminate noise. The lower end of this rod 95 21 (see Fig. 3) is pivoted at 23 to a horizontal rock shaft 24, this latter being pivoted at its ends in a bracket 25 that is rigidly secured to the motor frame 26. Fast on the rock shaft 24 is an upstanding brake 100 arm 27 carrying at its upper end a brake shoe 28 that cooperates with the periphery of a brake disk 29 fast on the governor shaft 30 of the motor. A coil spring 31 (Fig. 2) surrounding the rod 18 and abutting one end against the lug 17 and at its

other end against the collar 20 normally keeps the brake shoe applied to the brake disk, holding the motor idle. When, however, the rod 18 is shifted endwise toward the front end of the machine, the brake is released by the thrust of the collar 19 against the arm 21, and the motor is allowed to start. This is effected automatically upon the outward swinging movement of the tone arm by the following mechanism:

32 designates an arc-shaped slot formed in the table 5, through which projects a stud 33, preferably having rubber covering to eliminate noise and carried by one arm 34 of a bell crank lever that is pivoted at 35 to the underside of the table 5. The other arm 36 of this bell crank lever is connected by a link 37 to a lever 38 that, in turn, is pivoted between its ends at 39 to a table 5 and has a forked arm 40 straddling the rod 18. A collar 41 keyed on the outer end of the rod 18 forms an abutment for the lever arm 40 to render the latter effective on the rod; felt washers 42 being preferably interposed between arm 40 and the collar 41 and guide lug 17 to eliminate noise.

The means for holding the brake released during the playing of a record, and for automatically applying it at the conclusion of the playing of the record consists of the following mechanism:

Pivoted at 43 to the underside of the bar 13 is a trigger lever, one arm 44 of which is provided with a downwardly turned stop projection 44' that is adapted to swing into and out of the path of travel of the inner end of the rod 18. The other arm 45 of this lever has a bent end 45' that extends beyond the edge of the bar 13 and carries at its free end an upstanding stud 46 (Fig. 1) that projects through an arcuate slot 47 in the table 5. This trigger-lever is normally urged in a direction to carry its stop projection 44' across the path of travel of the rod 18 by a light spring 48 (Fig. 2); but in the brake-applying position of the parts represented in Fig. 2 the stop projection 44' is normally held against the side of the rod 18 by the spring 48. The bar 13 and the parts carried thereby may be shifted angularly so as to function properly on the records of different lengths by the simple lever and link mechanism shown, and comprising the following parts:

49 designates a vertical shaft journaled in the forward portion of the table 5 and provided on its upper end with a turning knob 50. On the lower end of this shaft is an arm 51 connected by a link 52 with one arm 53 of a bell-crank lever that is pivoted at 54 to the underside of the table 5; the other arm 55 of this lever being connected by a link 56 to the angularly shiftable bar 13. Obviously, by turning the knob 50 in one direction the bar 13 is swung away from the

center of the table, and by turning it in the opposite direction it is swung toward the center of the table.

A tension spring 57 connected at one end to the link 37 and at its other end anchored to a lug 58 secured to the underside of the table 5 serves to return the lever 38 and contact stud 33 to normal position after the brake has been released in the manner hereinafter described.

Describing now the operation of the mechanism, when a given record is to be played it is positioned on the usual turntable, and the tone arm is swung inwardly to a position wherein the stylus or needle occupies the innermost coil of the record groove, or a position slightly inward of the termination of the record, since the last few coils of the groove are usually blank. Since the arm 9 is rigid with the tone arm it simultaneously swings in the same direction, occupying, for example, the position shown by dotted lines in Fig. 1. The knob 50 is then turned swinging the bar 13 until the stud 46 lies in contact with the curved or cam edge 11 of the arm 9. At this time the brake is applied and the brake controlling devices occupy the relative positions shown in Fig. 2. The tone arm is then swung outwardly to carry the stylus into the outermost coil of the record groove, and in so doing the arm 9 strikes the stud 33, as shown by full lines in Fig. 1, thereby, through the lever and link connections previously described, shifting the rod 18 outwardly and releasing the brake, thus permitting the motor to start. At the same instant the spring 48 causes the stop lug 45 to swing across the inner end of the rod 18 thereby arresting the latter in its outwardly shifted position and holding the brake mechanism released, and at the same time moving the contact stud 46 slightly inwardly. As soon as the playing of the record is completed, the arm 9 strikes the stud 46 and rocks the trigger-lever, carrying the stop 45 away from the end of the rod 18, thus allowing the spring 31 to act and to instantly apply the brake and arrest the motor.

It will be observed that the brake-actuating arm 21 is so connected to the rock-shaft 24 (by the pivot 23) that its upper end is free to partake of the swinging movement of the bar 13 and rod 18 when setting the contact stud 46; and the forked end 40 of lever 38 is long enough to accommodate the maximum angular swing of rod 18 without becoming disengaged from the latter.

It is believed that the construction and operation of the present improvement will be readily understood from the foregoing without further detailed description. Manifestly the invention may be modified and varied from the precise details herein shown and described without involving any depar-

ture from the substantial character of the invention, or sacrificing any of the advantages thereof. Hence I reserve such variations and modifications as fairly fall within the 5 spirit and purview of the appended claims.

I claim:

1. In an automatic stopping mechanism for talking machines, the combination of a table, a member mounted to travel horizontally above said table, a motor-driven element, a brake for said element, a spring-actuated brake-applying mechanism, a trigger-lever for holding said brake-applying mechanism inoperative, said trigger-lever having a part lying in the path of travel of said member, and an angularly shiftable member carrying the actuating spring of said brake-applying mechanism and said trigger-lever.
2. In an automatic stopping mechanism for talking machines, the combination of a table, a member mounted to travel horizontally above said table, a motor-driven element, a brake for said element, a spring-actuated brake-applying mechanism, a trigger-lever for holding said brake-applying mechanism inoperative, said trigger-lever having a part lying in the path of travel of said member, a carrier for said trigger lever and the actuating spring of said brake-applying mechanism pivoted to said table, and manually operable means for shifting said carrier angularly to vary the position of said trigger-lever relatively to the path of travel of said member.
3. In an automatic stopping mechanism for talking machines, the combination of a slotted table, an arm mounted to swing horizontally above said table, a motor-driven element, a brake for said element, a pivoted brake-actuating arm, a carrier pivoted to the under side of said table, a spring-actuated rod slidably mounted on said carrier and engaged with said brake-actuating arm, a trigger-lever also mounted on said carrier and movable into and out of stop relation to said rod, a spring urging said trigger-lever into stop relation to said rod, and a contact stud carried by said trigger-lever and projecting through the slot of said table into the path of travel of said swinging arm.
4. In an automatic stopping mechanism for talking machines, the combination of a slotted table, an arm mounted to swing horizontally above said table, a motor-driven element, a brake for said element, a pivoted brake-actuating arm, a carrier-bar pivoted at one end to the under side of said table, a support on which the free end of said carrier-bar slidably rests, a spring-actuated rod slidably mounted on and lengthwise of said carrier-bar and engaged with said brake-actuating arm, a trigger-lever also mounted on said carrier-bar and movable into and out of stop relation to said rod, a spring urging said trigger-lever into

said trigger-lever into stop relation to said rod, a contact stud carried by said trigger-lever and projecting through the slot of said table into the path of travel of said swinging arm, and manually operable means 70 mounted on said table for shifting said carrier-bar angularly.

5. In an automatic stopping mechanism for talking machines, the combination of a slotted table, an arm mounted to swing horizontally above said table, a motor-driven element, a rock-shaft, a brake arm rigid on said rock-shaft and carrying a brake-shoe co-operating with said element, a brake actuating arm pivoted at its lower end on said 75 rock-shaft so as to swing lengthwise of the latter, a carrier-bar pivoted at one end to the under side of said table, a support on which the free end of said carrier-bar slidably rests, a spring-actuated rod slidably 80 mounted on and lengthwise of said carrier-bar and engaged with the upper end of said brake-actuating arm, a trigger-lever also mounted on said carrier-bar and movable into and out of stop relation to one end of 85 said rod, a spring urging said trigger-lever into stop relation to said rod, and a contact stud carried by said trigger lever and projecting through the slot of said table into the path of travel of said swinging arm.

6. In an automatic stopping and starting mechanism for talking machines, the combination of a table, a member mounted to travel horizontally above said table, a motor-driven element, a brake for said element, 100 a spring-actuated brake-applying mechanism, spring-actuated trigger-lever for holding said brake-applying mechanism inoperative, said trigger lever having a part lying in the path of travel of said member, an 105 angularly shiftable member carrying a part of said brake-applying mechanism and said trigger-lever, and mechanism for actuating said brake-applying mechanism to brake-release position and including a part lying 110 in the path of travel of said traveling member.

7. In an automatic stopping and starting mechanism for talking machines, the combination of a table, a member mounted to 115 travel horizontally above said table, a motor-driven element, a brake for said element, a spring-actuated brake-applying mechanism, a spring-actuated trigger-lever for holding said brake-applying mechanism inoperative, 120 said trigger-lever having a part lying in the path of travel of said member, a carrier for said trigger lever and a part of said brake-applying mechanism pivoted to said table, manually operable means for shifting 125 said carrier angularly to vary the position of said trigger-lever, and mechanism for actuating said brake-applying mechanism to brake-release position and including a part lying 130 in the path of travel of said member.

8. In an automatic stopping and starting mechanism for talking machines, the combination of a table, an arm mounted to swing horizontally above said table, a motor-driven element, a brake for said element, a pivoted brake-actuating arm, a carrier pivoted to the under side of said table, a spring-actuated rod slidably mounted on said carrier and engaged with said brake-actuating arm, a 10 spring-actuated trigger-lever also mounted on said carrier and movable into and out of stop relation to said rod, a spring urging

said trigger-lever into stop relation to said rod, a contact stud carried by said trigger-lever and projecting above said table into 15 the path of travel of said swinging arm, means for shifting said carrier angularly, and mechanism acting on said rod for actuating said brake-applying mechanism to brake-release position and including a contact stud projecting above said table into the path of travel of said swinging arm.

ALBERT A. HUSEBY.
